(57) CLAIM

The ornamental design for a liquid medication dispenser, as shown and described.

DESCRIPTION

FIG. 1 is a perspective view of a liquid medication dispenser showing our new design;

FIG. 2 is left side view thereof;

FIG. 3 is a right side view thereof;

FIG. 4 is a front view thereof;

FIG. 5 is a top view thereof; and,

FIG. 6 is a bottom view thereof.

The dashed lines immediately adjacent to the claimed areas in the views represent the boundaries of the claimed design and form no part of the claimed design.
